Attorney

UNITED STATES PATENT OFFICE

CARLOS B. MIRICK, OF WASHINGTON, DISTRICT OF COLUMBIA

REMOTE-CONTROL DEVICE

Application filed August 24, 1927. Serial No. 215,249.

(GRANTED UNDER THE ACT OF MARCH 3, 1883, AS AMENDED APRIL 30, 1928; 370 O. G. 757)

My invention relates broadly to remote control devices and more particularly to remote control devices for radio apparatus used upon radio controlled airplanes.

Two types of radio antennae have been used upon airplanes and each are adapted to their specific use. One type has been designated as the skid fin antenna and the other has been designated as the trailer antenna. The skid fin type of antenna is particularly adapted for use in reception or transmission of signals when the plane is upon ground or water, in which case it is practically impossible to use a trailer antenna.

However, the superiority of the trailer antenna over the skid fin type of antenna for use in flight is well known. This superiority of the trailer antenna is due not only to the greater effective height but also this type of antenna is farther from the sources of electrical disturbance upon the plane. For this reason the trailer antenna collects less local interference.

The primary object of my invention is to produce an automatic mechanism by which a trailing antenna may be substituted for the skid fin antenna while the plane is in the air.

A further object of my invention is to produce a means through which the skid fin antenna is automatically restored to its operative condition as an antenna upon the plane's landing or should the trailer antenna become disabled through contact with any object while the plane is in flight.

Further objects of my invention will appear more fully hereinafter as the description of the method and apparatus is developed.

My invention consists substantially in the construction, combination and arrangement of parts associated therewith or as will be more fully hereinafter set forth as shown by the accompanying drawings and finally pointed out in the appended claims.

Reference is to be had to the accompanying drawing forming a part of this specification in which numeral 1 represents the body of an airplane in which is mounted any of the usual type of remote control receivers 2. Under normal operating conditions the skid fin antenna 3 is directly connected to the receiver

2. During the take-off of the plane from land or water the signals are received upon the skid fin antenna 3, detected through an amplifier 4. These amplified currents operate relay 5 which in turn operates the selector 6. The selector 6 operates the various controls of the airplane when the plane is in the air.

After the plane is in the air, by the proper selection of signals the selector mechanism 6 may be activated in such a manner that it will operate the electro-magnet 7 which in turn actuates one end of the lever 8. This lever is pivoted at a point 9 in the body of the plane. The upper end of the lever is held under tension by spring 10 to prevent any accidental movement of the lever other than that produced by the action of the electro-magnet 7. The lower end of the lever 8 maintains the door 11 of a housing 12 in a closed position in the manner shown in the drawing. Within this housing is a free spool of antenna wire 13.

The inner end of the antenna wire is rigidly attached to the spool 13. The other end of the antenna wire passes through an opening 14 in the body of the plane and is attached to a multipole switch 15.

As long as the antenna spool is within the housing the switch 15 is held in contact with the grounded terminal 16 by means of a spring 17. When the lever 8 is released the spool of antenna wire falls from the housing 12 and unrolls until the spool hangs at the free end of the antenna. The weight of the antenna spool should be sufficient to shift the contact of switch 15 from the grounded terminal to the terminal 18 of the trailing antenna.

It is to be understood that a suitable loading of inductance or capacity is connected between the terminal 18 and the trailing antenna so that the change between the contacts produces no change in the tuning of the receiver.

During flight then, the trailing antenna acts as the true antenna and the skid fin antenna 3 serves as a counter-poise.

A weak link 19 is provided in the trailing antenna so that should the trailing antenna become entangled with an object either dur-

ing the flight or the landing of the plane the trailing antenna will be freed from the plane. By the release of the tension exerted by the trailing antenna upon the switch 15, the spring 17 automatically shifts the contact of the switch 15 from the terminal 18 to the grounded terminal 16. The receiver 2, then operates with the skid fin antenna 3 as the true antenna.

10 It will be understood that the above description and accompanying drawings comprehend only the general and preferred embodiment of my invention and that minor detail changes in the construction and arrangement of parts may be made within the scope of the appended claims without sacrificing any of the advantages of my invention.

15 The invention herein described may be manufactured and used by or for the Government of the United States for governmental purposes without the payment to me of any royalty thereon or therefor.

20 Having thus described my invention what I claim is as follows:

25 1. In a remote control radio device for airplanes including a radio receiver, an amplifier and a selective mechanism for operating the controls of the airplane, the combination of a skid-fin antenna connected to one side of the antenna circuit of the receiver, a connector grounded to the airplane upon the other side of the antenna circuit of the receiver, a trailer antenna and means for substituting the trailer antenna for the grounded connector in the antenna circuit, said means consisting of a switch operated by the weight of the trailer antenna.

30 2. In a remote control radio device for airplanes including a radio receiver, an amplifier and a selective mechanism for operating the controls of the airplane, the combination of a skid-fin antenna connected to one side of the antenna circuit of the receiver, a connector grounded to the airplane upon the other side of the antenna circuit of the receiver, a trailer antenna, and means for substituting the trailer antenna for the grounded connector in the antenna circuit, and means for restoring the grounded connector when the trailer antenna is disabled.

35 3. In a remote control radio device for airplanes including a radio receiver, an amplifier and a selective mechanism for operating the controls of the airplane, the combination of a skid-fin antenna connected to one side of the antenna circuit of the receiver, a connector grounded to the airplane upon the other side of the antenna circuit of the receiver, a closure member mounted upon the body of the airplane, a trailer antenna wound upon a spool and disposed within a box, a multipole switch in the antenna circuit of the receiver and means for releasing the spool and trailer antenna from the box, said trailer antenna operating the said multipole switch

for the substitution of the trailer antenna for the grounded connector in the antenna circuit.
